UNITED STATES PATENT OFFICE.

LAZARD KAHN, OF HAMILTON, OHIO, ASSIGNOR TO F. & L. KAHN & BROS.,
OF SAME PLACE.

DESIGN FOR A GAS-STOVE.

SPECIFICATION forming part of Design No. 21,332, dated February 2, 1892.

Application filed January 8, 1892. Serial No. 417,421. Term of patent 7 years.

To all whom it may concern:

Be it known that I, LAZARD KAHN, a citizen of the United States, residing at Hamilton, Butler county, Ohio, have invented and produced a new and original Design for Gas Heating-Stoves, (Case B,) of which the following is a specification, reference being had to the accompanying drawing, forming part thereof.

10 The drawing is a perspective view of a gas heating-stove, showing my design.

In the drawing, A indicates the body of the stove, which is semi-cylindrical; B, the base thereof, semicircular in plan; C, the open rectangular front of the body, extending the width of the body and extending vertically from the base to near the top; D, a rectangular top-plate surmounting the body; E, a frieze extending across the body below the top plate and forming the upper margin of the

front opening; F, an ornamental molding at the front edge of the base and extending from side to side of the body and forming the lower margin of the front opening; G, an ornamental foot-rail disposed forward of and ²⁵ parallel with the molding F; H, a corrugated curved reflector to the rear of the front opening and extending rearwardly and upwardly from the molding F, and J ornamented pilasters at each side of the front of the body and ³⁰ extending from the base to the frieze and forming the side margins of the front opening.

I claim—

The design for a gas heating-stove, as herein described and shown.

LAZARD KAHN.
